TOWEL LOCK RACK

Samuel Tritt, Bronx, N. Y.

Application December 28, 1948, Serial No. 150,403

Term of patent 3½ years

(Cl. D33—16)

To all whom it may concern:

Be it known that I, Samuel Tritt, a citizen of the United States, residing at the Bronx, New York, in the county of Bronx and State of New York, have invented a new, original, and ornamental Design for a Towel Lock Rack, of which the following is a specification, reference being had to the accompanying drawing, forming a part thereof.

In the drawing:

Fig. 1 is a perspective view of a towel lock rack, showing my new design;

Fig. 2 is a similar view showing the bracket member alone;

Fig. 3 is a similar view to Fig. 1, showing the sliding member alone;

Fig. 4 is a rear elevational view of Fig. 1;

Fig. 5 is a vertical sectional view taken on the line 5—5 of Fig. 1; and

Fig. 6 is another vertical sectional view, taken on the line 6—6 of Fig. 1.

I claim:

The ornamental design for a towel lock rack, as shown.

SAMUEL TRITT.
